UNITED STATES PATENT OFFICE

ISIDOR CHESLER, OF WEST ORANGE, NEW JERSEY, ASSIGNOR TO EAGLE PENCIL COMPANY, OF NEW YORK, N. Y., A CORPORATION OF DELAWARE

DESIGN FOR A MECHANICAL PENCIL

Application filed May 2, 1932. Serial No. 43,684. Term of patent 14 years.

To all whom it may concern:

Be it known that I, ISIDOR CHESLER, a citizen of the United States of America, residing at 28 Oxford Terrace, West Orange, New Jersey, have invented a new, original, and ornamental Design for a Mechanical Pencil, of which the following is a specification, reference being had to the accompanying drawing forming part thereof, in which

Figure 1 is a side elevational view of a mechanical pencil showing my new design.

Figure 2 is a bottom plan view of the same.

I claim:

The ornamental design for a mechanical pencil, as shown.

ISIDOR CHESLER.
